UNITED STATES PATENT OFFICE.

WILLARD G. RICH, OF ROCHESTER, NEW YORK.

SHAVING-STICK HOLDER.

1,299,032.

Specification of Letters Patent.

Patented Apr. 1, 1919.

Application filed June 7, 1918. Serial No. 238,658.

To all whom it may concern:

Be it known that I, WILLARD G. RICH, of Rochester, in the county of Monroe and State of New York, have invented certain 5 new and useful Improvements in Shaving-Stick Holders; and I do hereby declare the following to be a full, clear, and exact description of the same, reference being had to the accompanying drawings, forming a 10 part of this specification, and to the reference-numerals marked thereon.

My present invention has for its object to provide a holder for shaving sticks, which will afford an ample grip for the fingers of 15 the user; will enable the shaving stick, when not in use, to be supported in an upright position, adding thereto, in the first instance, a very desirable capability of attractive display; and which is so constructed 20 that the purchaser is not misled or deceived as to the quantity of material or soap comprising the shaving stick proper. A further object of the invention is to provide a device of this character, comprising few parts, 25 which is simple in construction and easily assembled, and from which the stub or unused end of the soap stick may be easily removed and another inserted. To these and other ends the invention consists in certain 30 improvements and combinations of parts, all as will be hereinafter more fully described, the novel features being pointed out in the claims at the end of the specification.

In the drawings:

35 Figure 1 is a side elevation showing a soap stick and a holder applied thereto constructed in accordance with my present invention.

Fig. 2 is a similar illustration showing a central cross sectional view of the holder.

40 Fig. 3 is a perspective view of the interior cup-shaped portion.

Similar numerals in the drawings indicate similar parts.

In a device of this character, it is desirable 45 able to provide a holder which is flat across the bottom or lower edge so that the soap stick, when not in use, may be supported in an upright or vertical position, and also give the holder a sufficient length to enable the 50 user to firmly grip it in his hand, as his hands are frequently wet or moist when the stick is used for the purpose intended. The flat bottom of the holder is desirable not only for the convenience of the user, but 55 also for the reason that it enables the goods to be readily displayed in an attractive man-

ner on the counters, and in the show-cases and windows of the store keepers. However, a disadvantage exists in adopting the previous construction of holders of this general character because lengthening the handle for the convenience of the user and for the additional advantages of display, which it affords, necessitates either providing a body of soap which is longer than 60 need be, if the handle is filled, or deceiving the purchaser if the soap stick only extends part way into the handle. The holder which I have devised, is hollow and overcomes these objectional features by showing 65 to the prospective purchaser exactly the length of the soap stick which he is purchasing.

In carrying out my invention I provide a 70 holder for a soap stick, indicated by 1, which is attached to its lower end by means of screw threads. The holder comprises an outer tubular member in the form of a broad ring, comprising a band portion 2, which may be of any desired length, and the upper 75 portion provided with screw threads indicated by 3, formed by rolling or crimping the sheet metal helically. The threaded portion of the holder I preferably make of lesser diameter than the band 2, thus providing 80 an annular shoulder 4 at the base of the screw threads. This shoulder positions the inner member, but it is not necessary that the shoulder be located at the particular point indicated. For instance, the shoulder might 85 be located at the point 5, or a second shoulder provided in this location, in which event it would be formed at the time the outwardly projecting annular rib 6 is made to form the abutment or stop co-operating 90 with the lower end of the cap or tubular case, which is usually provided as indicated in dotted lines in Fig. 1. When the shoulder 95 5 is provided, the lower end of the band portion of the holder is made slightly larger 100 in diameter as indicated at 2^a.

The inner member of the holder is cup-shaped and comprises an annular wall 7 fitting within the band 2—2^a, and provided with a top 8, which extends transversely the 105 holder to limit the entrance of the soap stick when turned into the screw threads. This wall, or partition 8, is for this reason preferably located at the bottom of the screw threads, and its edge butts against the 110 shoulder 4. The latter limits the movement of the inner or cup-shaped member in one

direction, or inwardly, and its removal or displacement in the other direction, or outwardly, is prevented by an interlocking engagement affected between the side walls of 5 the two members, which is preferably accomplished by a bead 9 on the lower end of the outer member, inclosing the lower edge of the wall 7 of the inner member.

To facilitate the removal of the stub end 10 or portion of the soap stick, which remains after the soap has worn down to the level of the upper edge of the screw threads 3, I provide in the top wall or partition 8 an aperture 8^a, which enables the operator to 15 grasp the remaining stub, or disk, of soap between the thumb and fingers by inserting the thumb through the bottom of the holder and the aperture 8^a into contact with the lower end of the soap, and by engaging the 20 latter with the first and second fingers of the same hand, the soap can be held while the holder is rotated to back the screw off and effect its disengagement.

I claim as my invention:

25 1. A shaving stick holder comprising a tubular member having substantially straight side walls and provided with an upper end of lesser diameter forming an annular shoulder and provided with an interior screw 30 thread, an inner cup-shaped member slipping within the interior of the tubular mem-

ber and limited in its inward movement by engagement with said shoulder, and having a bottom closing the outer member at the bottom of the screw thread, said members 35 having an interlocking engagement at their lower ends to prevent withdrawal of the inner member.

2. A holder for shaving sticks comprising an open cylindrical member having a band 40 portion with straight side walls and provided with an interior screw threaded portion above the band, an inner cup-shaped member having a bottom and side walls slipping and inserted within the band with 45 its bottom located below the screw threads, and a bead on the bottom edge of the band inclosing the edge of the side wall of the inner member.

3. A shaving stick holder comprising a 50 tubular member open at the ends and provided with an interior screw thread at one end and a partition fixed in said member below the screw thread intermediate the ends of the member to limit the inward movement 55 of a soap stick, and provided with an aperture adapted to permit opposite sides of the stub end of a soap stick in the holder to be engaged and held to facilitate the disengagement of the screw thread therefrom.

WILLARD G. RICH.
